United States Patent [19]

Fukuda et al.

[11] Patent Number: Des. 319,212

[45] Date of Patent: ** Aug. 20, 1991

[54] ELECTRICAL CONNECTOR

[75] Inventors: Kiyohito Fukuda; Takao Murakami, both of Kosai, Japan

[73] Assignee: Yazaki Corporation, Tokyo, Japan

[**] Term: 14 Years

[21] Appl. No.: 356,711

[22] Filed: May 25, 1989

[30] Foreign Application Priority Data

Dec. 7, 1988 [JP] Japan 63-47477

[52] U.S. Cl. D13/133

[58] Field of Search D13/133; 439/140, 320, 439/323, 357, 502, 578, 607

[57] CLAIM

The ornamental design for an electrical connector, as shown and described.

DESCRIPTION

FIG. 1 is a top plan view of an electrical connector showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a cross-sectional view thereof taken along line 7—7 of FIG. 3;

FIG. 8 is a cross-sectional view thereof taken along line 8—8 of FIG. 3; and

FIG. 9 is a cross-sectional view thereof taken along line 9—9 of FIG. 4.

FIG. 2

FIG. 1

FIG. 3

FIG. 4

FIG. 5

FIG. 6

FIG. 7

FIG. 8

FIG. 9
